TRAVERSE MECHANISM FOR WINDING MACHINES

Alfred Walter Arterton, Westfield, Mass., assignor to Foster Machine Company, Westfield, Mass., a corporation of Massachusetts

Application April 18, 1941, Serial No. 389,134

5 Claims. (Cl. 242—43)

This invention relates to winding machines and more particularly to the means for traversing the guide which lays the yarn or thread in place on the core upon which the yarn is wound to build up the package.

One object of my invention is to provide means to produce a variable traverse of the yarn guide and consequently a variable lay of the yarn coils in succeeding layers. A further object is to provide mechanism for controlling the position of the yarn guide in its traversing movement to produce a novel yarn package having tapered or rounded ends. A further object is to wind a package so that the coils at the end of the package are long and looping in contra-distinction to regular short and angular coils. A still further object is to build a winding package so that a binding of the helical coils, particularly at the ends of the package is provided to insure free unwinding delivery of the strand over the end of the supply package.

Other and further objects of the invention will be made apparent in the following specification and claims.

In the accompanying drawings,

Fig. 1 is a front elevational view of a winding machine embodying the present invention, with parts broken away;

Fig. 2 is a right side elevational view of the structure shown in Fig. 1;

Fig. 3 is a detail sectional view substantially on line 3—3 of Fig. 1, on a somewhat larger scale;

Fig. 4 is a detail plan view of the yarn guide and cam;

Fig. 5 is a view similar to Fig. 4 but showing the parts positioned for subsequent cycle of operation;

Fig. 6 is a detail view of the ratchet cam;

Fig. 7 is a detail view looking from the right of Fig. 6 and including the ratchet actuating pawl;

Fig. 8 is a fragmentary detail view of a portion of the structure as in Fig. 2 but showing a modified form of yarn guide;

Fig. 9 is a fragmentary detail plan view of the structure shown in Fig. 8; and

Fig. 10 is a view similar to Fig. 4 but showing a multiple yarn guide arrangement.

Referring to the drawings, 10 indicates a housing supported on any suitable frame or base as indicated at 9 in Fig. 2. A package supporting spindle 11 is rotatably supported in bearings, one of which is shown at 12, mounted on housing 10.

A traverse cam shaft 13 is journaled in suitable bearings carried by the housing 10, one of which bearings is shown at 14 in Fig. 1, the bearing bushing being indicated at 15. The spindle 11 and shaft 13 are geared together for simultaneous rotation at predetermined relative speeds in the usual manner by gearing not shown. The spindle 11 supports a drum 16 adapted to receive a package core 17. Shaft 13 carries a traverse cam 18 of conventional form secured thereto by a set screw 19.

It will be understood that in the present embodiment of my invention, the rotation of the traverse cam shaft 13 will be so related to the rotation of the spindle 11, as to provide a lay of the yarn in relatively wide open spaced apart helical coils. This in conjunction with the manner of looping the end coils as will be described, will build up a package for easy and smooth unwinding thereof under all conditions of handling present day yarns, such as cotton, silk, rayon, Nylon, and yarns of other synthetic compositions.

A guide support, generally indicated at 20 (Figs. 2 and 3) is supported on shaft 13 by an arm 21 formed integral with support 20 and having a hub portion 22 fitting on bushing 15 exteriorly of housing 10. The support 20 is held in fixed position by a locking link 23 connecting the free end of arm 21 to a stud 24 secured to housing 10.

A traverse guide bar 25 is secured in one end of support 20 by a set screw 26 (Figs. 1 and 2), the other end being similarly secured within housing 10 to the opposite end of support 20, not shown. A traverse tube 28 is slidably mounted on bar 25 and is provided at one end with a cam follower 29 engaging in the groove 30 of traverse cam 18. The outer end of tube 28 has fixed thereto a block 31 which may be secured thereto in any suitable manner said assembly serving as the yarn guide carrier. As shown, a plate 32 (Fig. 3) is welded or otherwise secured to tube 28 and an intermediate plate 33 is welded or otherwise secured to plate 32. Block 31 is recessed at its back to receive plate 33 and is secured thereto by a machine bolt 37. As best shown in Fig. 3, the bar 25 and traverse tube 28 are positioned in a recess 38 formed in the support 20 and the upper end of plate 32 slides along a machined surface 39 above recess 38 and beneath a cover plate 40 secured at its ends to support 20 by machine screws 41 (Fig. 1).

A yarn guide 45 is pivotally mounted at the lower end of block 31 by means of a pin 46 ro-

tatably mounted in block 31. Pin 46 is provided at its lower end with an enlargement or head 47 in which the yarn guide 45 is secured by set screw 48. The upper end of pin 46 carries a cam follower 50 secured adjustably thereto by set screw 51. A friction washer 52 is positioned between cam follower 50 and block 31, which in combination with a spring tension washer 53 positioned between head 47 and the adjacent end of block 31 frictionally holds pin 46 and the yarn guide 45 carried thereby in the various positions to which it is moved by cam follower 50, as later disclosed. From the mechanism so far described, it will be apparent that block 31 is reciprocated in strokes of fixed length in a parallel longitudinal direction relative to spindle 11, by cam 18.

Successive pivotal movements are imparted to pin 46 at one or both ends of the traversing stroke of block 31 by engagement of follower 50 with one or the other of the slope cams 55 and 56 formed at the opposite ends of and at an angle to a cam plate 57 said cam assembly serving as a yarn guide actuator as will be explained. The upper edge of plate 57 is bent rearwardly to form a flange 58 and is slidably supported on the similarly rearwardly bent edge or flange 59 of cover plate 40. The flange 59 is provided with guide studs 60 which extend through guide slots 61 formed in flange 58 of cam plate 57. Nuts 62 threaded on studs 60 hold the cam plate in guided position on the studs.

Cam plate 57 is given a relatively slow reciprocation by means of a face cam 65 (Figs. 1, 6, and 7) rotatably mounted on a stub shaft 66 secured in the free end of an arm 67 which is bolted at 68 to support 20. As best shown in Figs. 1 and 2, reciprocation is imparted to cam plate 57 from cam 65 through an arm 70 secured at 71 to an extension 72 of cam slope 55. The opposite end of arm 70 is fixed at 73 to the inner end of a rod 74 slidably mounted in arm 21 and a bracket 75 extending from support 20. Rod 74 carries a cam roll 76 which engages face cam 65 and is held in operative relation therewith by a compression spring 77 surrounding rod 74 and compressed between a collar 78, fixed to the rod 74, and bracket 75.

Relatively slow rotation is imparted to face cam 65 by means of a ratchet 80 to which the cam is secured by machine screws 81 (Fig. 7). The ratchet 80 is driven by a pawl 82 actuated by an eccentric 83 upon which the pawl is mounted. The eccentric 83 is carried by a collar 84 adjustably secured to shaft 13, upon which traverse cam 18 is also mounted. Pawl 82 is held in proper operative relation to the ratchet 80 by a leaf spring 85 secured to arm 21 as by machine screw 86.

With each revolution of shaft 13 block 31 is given one complete reciprocation and the eccentric 83 also makes one revolution to advance ratchet 80 and cam 65 to slightly shift plate 57 and its cam longitudinally of the spindle 11.

The effect of the shifting of cam plate 57 is to vary the position of the thread or yarn spiral lays on the core 17—the said lays being successively offset from each other by small amounts towards one end of the core as the follower 76 ascends to the peak of face cam 65 and then towards the other end of the core, as the follower descends. The result is that a yarn package P having tapered ends is produced as shown in Figs. 4 and 5.

I am aware that tapered end packages have

been made by longitudinally shifting the stroke of the traverse as by a progressive and bodily shift of the traverse cam together with its yarn guide relative to the cam shaft. By my construction the stroke imparted by traverse cam 18 may, and preferably does, remain fixed in both length and position, and the shift of the yarn lays is effected by altering the position of the yarn guide first at one end of its traverse and then at the other end of its traverse.

Referring to Fig. 4, the fixed traverse imparted by traverse cam 18 is represented by the extreme positions of pin 46 indicated by dotted and solid lines. It will be assumed that cam plate 57 has been shifted to its extreme left hand position as viewed in Fig. 4 and that as pin 46 has reached its full line position, follower 50 has contacted slope cam 55 and has turned pin 46 and yarn guide 45 to the position shown in full line. As pin 46 and the yarn guide 45 are moved to the dotted line position by traverse cam 18 the yarn is laid on the core 17 in its extreme left hand position. When pin 46 and the yarn guide again return to the left after the next reciprocation, follower 76 has made its initial step in the descent of cam 65 and has moved cam plate 57 one increment to the right (Fig. 4). Follower 50 therefore contacts slope cam 56 and pin 46 at the end position of its stroke, is turned a slight amount clockwise so that yarn guide 45 does not reach its previous extreme left hand position but is moved to the position indicated in dotted lines at x in Fig. 5, thus offsetting the ensuing lay of yarn to the right. On each succeeding reciprocation of the yarn guide succeeding increments of movement of cam plate 57 to the right eventually tilt the yarn guide to the position shown in full line in Fig. 5 so that as the guide moves to the right to the dotted line position y the yarn is laid on the core in its extreme right hand position. Follower 76 now ascends cam 65, bringing slope cam 55 into operation to gradually return the yarn guide to the position of Fig. 4. This operation is repeated until the desired size of package has been wound on the core, the repeated offsetting of the yarn lays to the right and left giving a tapered form to the ends of the package P.

The swinging movement of the yarn guide at the end of its traverse has the result that the pitch of the convolutions at that end of the package is shorter than at the center of the package and the bend of the yarn as it reverse its direction toward the opposite end of the core instead of being sharply angular is more wide and looping, resulting in a secure binding of the helical coils at the end of the package, and assuring a subsequent free unwinding delivery of the yarn from the package in use. These advantages are not secured by a steady displacement of the traverse cam itself as in previous machines.

In Figs. 1, 2, 4, and 5 the yarn guide is shown as comprising a wire having a single angular bend, the yarn being led to the core 17 upwardly between the core and support 20 (Fig. 2) and from a source outwardly of the free end of the core, (Fig. 1). With this arrangement the yarn A at the start of the winding operation normally rests in the bend of the guide 45, but as the package grows, the yarn slides rearwardly on the guide as indicated at A' in Fig. 2, thus shortening the effective radius of the pivotal movement of the guide at the ends of the traverse. As a result, there is a gradual decrease in the offsetting of the lay of yarn as the package builds up. A

uniform offsetting may also be secured if desired by use of a yarn guide such as shown in Figs. 8 and 9, where the yarn guide 90 is shown secured to the top of cam follower 50 by a set screw 91, the various operating parts being as previously described. Yarn guide 90 is bent to provide an eye 92 at its end which maintains a constant radius of swing for the yarn A regardless of the growth of the package P'.

Both forms of yarn guide above discussed are maintained out of contact with the package, and the degree and character of movement given the yarn guide relative to its support is predetermined by the slope and spacing of cams 55 and 56 and by the shape of cam 65 and the rotative position of the latter on shaft 66.

Fig. 10 shows somewhat diagrammatically a modified structure by which a plurality of packages B, B', are simultaneously wound on one machine. As shown, two pivot pins 95 and 96 are provided, mounted on common support for being given simultaneous traverse movements longitudinally of the spindle, as previously described with respect to pin 46. Each pin 95 and 96 carries its respective yarn guide 97 and 97'. The pins 95 and 96 are respectively provided with cam followers 98 and 99 which respectively cooperate with the cams 55 and 56 previously described. The cam followers 98 and 99 are connected together for simultaneous movement by a link 100. Thus the movement imparted to follower 98 by cam 55 is transmitted to follower 99 and similarly actuation of follower 99 by cam 56 is transmitted to follower 98. As will be evident, the modification shown in Fig. 10 simultaneously winds two packages B and B' exactly similar in build to package P previously described.

I claim:

1. In a winding machine including a rotatable package supporting spindle, a yarn guide carrier, means to reciprocate said carrier longitudinally of the spindle, a yarn guide pivotally mounted on the carrier, a cam follower secured to the pivot of the yarn guide, a cam plate mounted for reciprocation parallel to the path of reciprocation of the yarn guide carrier, cams carried at opposite ends of said plate and respectively engageable with said follower at opposite ends of the path of reciprocation of the yarn guide carrier, and means to reciprocate said cam plate at a slower rate than the yarn guide carrier to effect a succession of engagements of the follower with one of said cams as said plate moves in one direction to successively swing the yarn guide towards one end of the spindle, and effect a succession of engagements of the follower with the other of said cams as the plate moves in the opposite direction to successively swing the yarn guide toward the opposite end of the spindle.

2. In a winding machine including a rotatable package supporting spindle, a yarn guide carrier, means to reciprocate said carrier longitudinally of the spindle in a path of fixed length, a yarn

guide pivotally mounted on the carrier, a cam follower secured to the pivot of the yarn guide, a cam plate mounted for reciprocation parallel to the path of reciprocation of the yarn guide carrier, cams carried at opposite ends of said plate and respectively engageable with said follower at opposite ends of the path of reciprocation of the yarn guide carrier, and means to reciprocate said cam plate at a slower rate than the yarn guide carrier to effect a succession of engagements of the follower with one of said cams as said plate moves in one direction to successively swing the yarn guide towards one end of the spindle, and effect a succession of engagements of the follower with the other of said cams as the plate moves in the opposite direction to successively swing the yarn guide toward the opposite end of the spindle.

3. In a winding machine, including a rotatable package supporting spindle, a yarn guide carrier having a traversing movement through a fixed stroke, a yarn guide movably mounted on said carrier, a yarn guide actuator having means for changing the position of said yarn guide on said carrier, and means for reciprocating said actuator slowly as compared with said traversing carrier to periodically shift the action of said yarn guide positioning means from one end of said traversing stroke to the other end of said traversing stroke.

4. In a winding machine, including a rotatable package supporting spindle, a yarn guide carrier having a traversing movement through a fixed stroke, a yarn guide movably mounted on said carrier, an actuator having means for changing the position of said yarn guide on said carrier, said positioning means acting on said yarn guide to shift the effective traversing movement of said yarn guide by a series of successive increments in one direction when located at one end of said traversing stroke and then by a series of successive increments in the other direction when located at the other end of said traversing stroke, and means for reciprocating said actuator slowly as compared with said traversing carrier to periodically shift the action of said yarn guide positioning means from one end of said traversing stroke to the other end of said traversing stroke.

5. In a winding machine, including a rotatable package supporting spindle, a yarn guide carrier having a traversing movement through a fixed stroke, a yarn guide movably mounted on said carrier, an actuator comprising a cam plate having a slope cam at each end thereof for positioning said yarn guide, one of said slope cams being located adjacent each end of said traversing stroke, means for reciprocating said actuator slowly as compared with said traversing carrier to periodically shift the action of said slope cams from one end of said traversing stroke to the other end of said traversing stroke.

ALFRED WALTER ARTERTON.
